UNITED STATES PATENT OFFICE.

PURVA V. CARPENTER, OF WORTH, NORTH CAROLINA.

BRAKE AND LEVER LOCK.

1,135,435.

Specification of Letters Patent. Patented Apr. 13, 1915.

Application filed December 27, 1913. Serial No. 808,944.

To all whom it may concern:

Be it known that I, PURVA V. CARPENTER, a citizen of the United States, residing at Worth, in the county of Gaston and State of North Carolina, have invented new and useful Improvements in Brake and Lever Locks, of which the following is a specification.

The invention has for an object to enable the construction of a lock for brake and gear shift levers in such a manner that the lock may be operated and made a part of the handle of the lever while yet preventing the lever from being released by severance of latch connections depended upon to hold it in set position.

A further object is to provide a novel form of grip release and a lock especially fitted for use therewith.

Additional objects and advantages will appear, some of which will be apparent from the following description, and from the drawings, in which,

Figure 1 is a side view of a brake lever constructed in accordance with my invention. Fig. 2 is a detail cross section on the line 2—2 of Fig. 1. Fig. 3 is a vertical sectional view of the lever. Fig. 4 is a detail cross section showing the mounting of the latch plunger. Fig. 5 is a vertical section detail of the mounting of the latch. Fig. 6 is a side view of a foot lever constructed in accordance with my invention. Fig. 7 is a detail section of the grip release. Fig. 8 is a cross section on the line 8—8 of Fig. 1.

There is illustrated a lever 10 formed of sheet metal, being taken from a suitable blank bent into U-shape transversely with the closed side toward the rear. The lever 40 is shaped or constructed at the lower end in any suitable way for engagement with devices to be operated. A short distance from its lower end the closed side is formed with an opening 11 through which a segment 12 of suitable construction is engaged slidably. At the front side above this segment the forward edges of the metal are turned inwardly in a suitable manner to close access to the space within the lever, also adding strength to the lever. This in-turned edge may be continued downwardly on each side of the segment 12, if desired, though it will have to be cut away slightly to admit the segment. The upper end of the lever is formed with an oblique portion 13 of suitable inclination for a handle. The edge portions of the handle are turned inwardly for a short distance as at 14, and if desired, a tongue portion 15 may be extended from the closed side of the lever and 60 brazed or otherwise fixed under the in-turned edge portions. Pivoted within the handle portion 13 rearwardly of and above the lower edge of the front closed part, there is the reduced end of a release grip 16 normally extending outwardly through the open side of the handle portion, checked at the outer limit of its movement by the upper closed part of the handle. It is shaped so as to move into the handle a distance, its 70 lower part lying slightly within the handle while at the outer limit of its movement. It is slotted at its lower end to receive the bolt 17 of a lock 18 carried between the sides of the lever immediately below the grip 16, and 75 mounted to be engaged by the grip when moved inwardly, there is a sliding bolt 19 having its upper end beveled toward the front, so as to be engaged and borne downwardly by the grip when forced inwardly. 80 The bolt may be set against the rear side of the lever and confined at the front by the lock member and the in-turned edge portions of the lever. The lock may be of any desired construction suitable for the purpose. 85 The bolt is held at the upper limit of its movement by a spring 20 bearing against its lower end and seated on a suitable support 21 between the sides of the lever. Slidably in the lower part of the lever, beneath the 90 segment 12, there is a latch 22, held between the closed rear side of the lever and the in-turned forward edge portions 23. The latch is extended up beside the segment as at 24, and inwardly over the segment, a link 25 95 being connected centrally thereto and extended upwardly past the support 21 and screwed into the lower end of the bolt 19, which is suitably bored and threaded for the purpose.

It will be understood that my invention is readily adaptable to use in foot-brakes or other foot levers, and in Fig. 6 I have illustrated an embodiment of a foot lever in which the lever proper 30 is constructed in a manner similar to that 10 before described, the lever being considerably shortened, however, and a member 31 corresponding to the grip 16 is mounted in the upper end of the lever, having, however a foot-receiving plate 32 extended some distance above the pivot of the member 31, whereby, when

the foot is pressed high thereon the latch is not disengaged. The remaining construction of the device may be the same as that before described.

- 5 It will be seen from the foregoing that a brake lever, latch and lock of an extremely simple construction are provided, which may be produced at a low cost and are adapted to be operated with great facility
10 and certainty. It has also the advantage that the connections between the latch and the releasing device are concealed and protected so that when the release is locked these connections cannot be readily severed. The
15 lever 30 may be moved rearwardly to normal position by a spring in any customary manner, not shown.

A secure lock is provided which does not interfere with the quick operation of the
20 device and also does not involve any parts liable to loss or easy derangement.

What is claimed:

1. A lever having a latch device thereon, a pivoted latch releasing member on the
25 lever and having a lock casing forming a fixed part of the lever, and having a bolt arranged, disposed and operative to project into the path of oscillation of the pivoted member at times, the pivoted member having a part constructed and arranged to engage the projected bolt whereby releasing movement of the pivoted member will be prevented.
2. A lever comprising a hollow body having a handle and a pivot portion, the handle being open at one side, the opening stopping short of the outer end of the handle, a latch releasing member pivoted in the handle longitudinally outward of the opening,
40 whereby it will engage the outer wall of the opening under outward movement and hav-

ing a portion projected outwardly through the opening and extended to be clasped with the handle, a lock fixed on the lever immediately adjacent the oscillating extremity 45 of the pivoted member when at the outer limit of its movement, the lock including a bolt to be shot into the path of the pivoted member, a latch slidable on the lever, and means within the body of the lever operative under pivotal movement of the pivoted member to operate the latch.

3. A lever of the class described comprising a hollow body and handle constructed for pivotal mounting, a notched segment, a 55 latch slidable in the lever constructed to engage the notched part of the segment at one limit of its movement, the handle having an opening at one side, a sliding bolt in the body of the lever having an outer end 60 beveled on the side toward the opening and projected thereunder, resilient means holding the bolt at this limit of its movement, a release member pivoted in the outer part of the handle and having its inner part disposed adjacent the inner edge of the bevel of the bolt and being movable inwardly to bear the bolt downwardly under sliding engagement therewith, the release member having an extension projected outwardly 70 through said opening, and a lock on the lever at the inner side of the opening including a locking member movable into the path of the release member.

In testimony whereof I have hereunto set 75 my hand in presence of two subscribing witnesses.

PURVA V. CARPENTER.
